WHEELED TOY

Edward S. Savage, Rochester, N. Y.

Application October 7, 1944, Serial No. 557,633

8 Claims. (Cl. 46—107)

1

The present invention relates to wheeled figure toys in which the toy is designed to be pulled or propelled along a supporting surface and one or more parts thereof are given movements imitating movements of the simulated living subject. However certain features of the invention are also applicable to other types of wheeled vehicles which may or may not be classified as toys.

The primary object of the invention is to provide an extremely simple form of wheeled toy or other vehicle which will guide itself to travel a sinuous course when pulled or propelled along a supporting surface. A further object of the invention is to provide guiding means consisting of one or more guiding wheels carried by an axle which is actuated to oscillate horizontally by rotation of said guiding wheel or wheels only. A further object of the invention is to provide a simple form of wheeled figure toy having a head member adapted for horizontal turning movement and means to cause the head to oscillate so that it will constantly face in the direction of travel of the toy. Other objects will appear as the description proceeds.

In the accompanying drawing I have illustrated one embodiment of my invention as incorporated in a pull toy simulating a swimming duck but it will be understood that the invention can be otherwise embodied and that the drawing is not to be construed as defining or limiting the scope of the invention, the claims appended hereto being relied upon for that purpose.

In the drawing:

Fig. 1 is a plan view of the improved toy with the upper forward portion taken in horizontal section approximately on line 1—1 of Fig. 2, showing guiding wheels and head member turned to the left.

Fig. 2 is a vertical section taken approximately on line 2—2 of Fig. 1, showing guiding wheels and head member in straight ahead position.

The same reference numerals in the two views indicate the same parts.

The toy in the preferred form includes a hollow body shown here as constructed of wood, comprising the top board 12, front molding 13, rear molding 14 and side plates 15 and 15'. The toy is provided with two pairs of wheels, front wheels 16 and 16' and rear wheels 17, both pairs of which are entirely enclosed within the toy body except on the under side. The front wheels 16 and 16' function as guiding wheels to guide the toy when it is being pulled along a supporting surface by means of the pull string 18. The guiding wheels 16 and 16' are fast on the ends

5 of the short axle 19 which is journaled in the swivel block 20. The swivel block 20 is fast on the lower end of the vertical pivot pin 21 and the head and bill member 22 is fast on the upper portion of the pivot pin 21, while the center portion of the pin is free to turn in the bearing hole 21b in the top body board 12. The head and bill member 22 is set in alignment with the guiding wheels 16 and 16' so that when the wheels 10 are in position for straight ahead travel the head and bill will be facing straight ahead.

A link 23 is pivoted freely at one end to a pin 24 which projects inside the body plate 15. This pin 24 is preferably located some distance to the 15 rear of and horizontally in line with the axle 19. The other end of the link 23 fits loosely over a pin 25 which projects from the outer face of the wheel 16 at an eccentric position thereon, being offset from the wheel center by the distance E as shown. It is to be noted that the 20 length of the link 23, between centers of the holes, is substantially equal to the horizontal distance from the center point of the axle 19 to the center of the pin 24, measurement being 25 taken in side elevation as in Fig. 2. When the wheels 16 and 16' are caused to rotate, the link 23 being connected from pin 24 to pin 25 serves to retain the pin 25 against any substantial horizontal motion while permitting vertical movement of the pin 25 for a distance equal to twice the offset distance E. It is obvious that, since 30 movement of the pin 25 is so restricted by the link 23, rotation of the wheels 16 and 16' will cause reciprocal angular movement or oscillation 35 of the whole pivoted assembly of the wheels, the swivel block 20 and head and bill member 22, about the axis of the pivot pin 21. Fig. 1 shows the extreme left hand position of the guiding 40 wheels, the corresponding position of the head and bill member being shown in full lines at 22. The extreme right hand position of the head and bill member is indicated by the dotted lines at 22'. The result of this angular oscillation of the 45 guiding wheels 16 and 16', when the toy is being pulled along a supporting surface, is to cause the toy to travel a sinuous course and the head and bill member 22, turning in unison with the guiding wheels, give the figure the interesting and amusing effect of "looking where it is going."

The rear wheels 17 may be tight on the axle 26 which turns freely in bearings in the body side plates 15 and 15', or the wheels may fit freely on the axle with said axle fitting tightly in the side plates 15 and 15'.

55 It will be apparent that I have provided in this

invention an extremely simple and inexpensive construction whereby swiveling movement of a guiding wheel is actuated by rotation of said guiding wheel only, resulting in sinuous travel of the toy when pulled along a supporting surface.

I am aware that swiveling movement of guiding wheels has been accomplished in other toy vehicles by more complex and expensive constructions wherein reciprocal connecting means actuated by some moving part of the vehicle, other than the guiding means, causes the guiding wheel or wheels to oscillate. Illustrative of such constructions the following is a list of patents with which I am familiar, all of which disclose forms of such mechanically actuated guiding means: Flaherty, No. 725,432; Lewis et al., No. 1,343,834; Ciaffone, No. 1,217,704; de Filippis, No. 1,332,545; de Filippis, No. 1,357,491; de Filippis, No. 1,756,539; and Pellerin, No. 1,988,396.

Whereas the accompanying drawing illustrates my invention in the form of a pull toy only, it is evident that the invention may be similarly applied to toys utilizing some self propelling means such as an electric motor or spring motor drive. If some such driving means is utilized it would most conveniently be installed within the body and connected to drive the rear wheels 17. It is apparent that the use of some such self propelling means does not in any way affect the essential features of this invention as herein shown and described.

I claim:

1. A wheeled vehicle movable over a supporting surface comprising a body, a horizontally swiveling guiding wheel having an eccentrically positioned pin projecting laterally from said wheel, and means to restrain said pin against substantial horizontal movement in relation to the body while permitting unrestricted vertical movement of the pin when the guiding wheel rotates.

2. A wheeled vehicle movable over a supporting surface comprising a body, a horizontally oscillating guiding wheel and means to cause oscillating movement of the wheel to guide the vehicle along a sinuous course while said wheel rotates comprising connecting means eccentrically positioned on said wheel, and a control member mounted on a stationary pivot on the body and coacting with said connecting means to control movement of said connecting means to cause horizontal oscillation of said wheel.

3. A wheeled vehicle movable over a supporting surface comprising a body, a guiding wheel mounted on said body to rotate about an approximately horizontal axis and to oscillate about an approximately vertical axis, and means positioned eccentrically with respect to both of said axes and turning bodily with said wheel as it rolls over said surface, for oscillating said wheel about said approximately vertical axis.

4. A wheeled vehicle movable over a supporting surface comprising a body, a guiding wheel mounted on said body to rotate about an approximately horizontal axis and to oscillate about an approximately vertical axis, connection means positioned eccentrically with respect to both of said axes and turning bodily with said wheel as it rolls over said supporting surface, and link means connecting said body to said connection means to restrain substantial horizontal movement of the latter with respect to the body to

cause oscillation of said wheel about said approximately vertical axes as it rotates about said approximately horizontal axis.

5. A wheeled vehicle movable over a supporting surface comprising a body, a pair of guiding wheels spacedly positioned on a common axle and adapted to oscillate approximately horizontally about an intermediate approximately vertical axis, a pin eccentrically positioned on and projecting from the outer face of one of said wheels, and a control member connected to the body and acting on said pin to restrict movement thereof in a horizontal direction in relation to the body and thereby to effect approximately horizontal oscillating movement of the guiding wheels about said approximately vertical axis to guide the vehicle along a sinuous course when the vehicle is caused to move over a supporting surface.

6. A wheeled figure toy movable over a supporting surface comprising a body, an upwardly extending shaft adapted to turn in said body, a substantially horizontal axle mounted on the lower portion of said shaft, a guiding wheel mounted on said axle, a head member positioned in facial alignment with said wheel and fixedly carried by and turning with the upper portion of said shaft, a pin eccentrically positioned on and extending laterally from said wheel at a point to one side of said shaft, and a control member connected to the body and acting on said pin to restrict movement thereof in a horizontal direction in relation to the body and thereby to effect oscillation of said wheel and shaft and attached head member, thus causing the vehicle to be guided along a sinuous course and the head member to move to constantly face in the direction of travel when the vehicle is caused to move over a supporting surface.

7. A wheeled vehicle adapted to be propelled over a flat surface, said vehicle including a circular guiding wheel mounted for concentric revolution about an approximately horizontal axis concentric with said wheel, by frictional engagement with the surface over which the vehicle is propelled, and also mounted for oscillation about an approximately vertical axis to cause the vehicle to move in varying directions, and means operated by the revolution of said wheel about said horizontal axis for causing oscillation thereof about said vertical axis, so that the vehicle will travel in a sinuous path.

8. A construction as described in claim 7, in which said means for causing oscillation about said vertical axis comprises a link pivoted at one end to said wheel eccentrically of both of said axes, and extending in a generally horizontal direction to a connection with the body of said vehicle, and restrained against movement in said horizontal direction, so that as said wheel turns about said horizontal axis the reaction of said wheel against said link causes said wheel to turn also about said vertical axis.
